UNITED STATES PATENT OFFICE.

HENRY D. GRAVES, OF GRANT PARK, ILLINOIS.

PORTABLE CASE FOR HONEY, EGGS, BREAD, AND THE LIKE.

1,284,317.

Specification of Letters Patent. Patented Nov. 12, 1918.

Application filed March 23, 1918. Serial No. 224,159.

To all whom it may concern:

Be it known that I, HENRY D. GRAVES, a citizen of the United States, residing at Grant Park, in the county of Kankakee, State of Illinois, have invented a new and useful Portable Case for Honey, Eggs, Bread, and the like; and I do hereby declare the following to be a full, clear, and exact description of the invention, such as

10 will enable others skilled in the art to which it appertains to make and use the same.

This invention relates to an improved portable case for honey, eggs, bread and the like, and one of the objects of the invention 15 is to provide a device of this kind, whereby honey, eggs, bread and the like may be more efficiently, conveniently and easily carried or transported.

A further object of the invention is to 20 provide a case for receiving honey frames, removably, enabling them to be transported without breakage.

A further object of the invention is the provision of a shipping case, so constructed 25 that honey frames may be compactly installed therein, either through the front or through the top.

A further object of the invention is the provision of a shipping case or box, which, 30 after reaching its destination with the honey frames therein, may be used as a display case, it being the aim that the front of the case be lowered, to be used as a support for the honey frame.

35 A further object of the invention is to provide a honey case of this kind, which is simple, efficient and inexpensive in construction, and comprises improved features in mechanical design.

40 In practical fields the details of construction may necessitate alterations falling within the scope of what is claimed.

The invention comprises further features and combination of parts as hereinafter set 45 forth shown in the drawings and claimed.

In the drawings:—

Figure 1 is a view in perspective of the improved honey or shipping case showing

the same constructed in accordance with the invention, and the front and top closed. 50

Fig. 2 is a vertical sectional view on line 2—2 of Fig. 1.

Fig. 3 is a perspective view of the shipping case or box showing the front section open and the top raised, so that the honey 55 frames may be supported on said front section.

Referring more especially to the drawings 1 designates the body section of the honey case or box, which comprises the 60 back piece 2, the bottom piece 3 and the side pieces 4. The back piece 2 is secured to the corresponding piece 4 and to the rear edge of the bottom piece 3. The lower portions of the side piece 4 are secured to the 65 end edges of the bottom piece, the forward portion of which projects beyond the forward edges of the side pieces 4. The lower ends of the outer side faces of the side pieces 4 have transverse recesses 5 for the reception of the metallic straps 6, which are secured to the side pieces 4 by the screws or the like 7. These metallic straps extend forwardly and are in parallelism with the end edges of the bottom piece 3. The front section of the box or case comprises the front 70 piece 8, and the side pieces or rails 9. The front piece 8 is secured on the front edges of the side pieces 9. The lower portions of the outer faces of the side pieces 9 and the 75 lower parts of the edges of the front piece 8 have recesses 10, and the forward ends of the metallic straps 6 engage the recesses 10 of the side pieces. In other words the lower ends of the side pieces 9 are reduced 80 and are pivoted on the pins 11, between the forward ends of the straps 6 and the end edges of the bottom piece 3, whereby the front section of the case or box may be easily closed or thrown downwardly and forwardly. When the front section is closed 85 the edges 12 and 13 of the side pieces 4 and 9 respectively engage. The lower part of the front edge of the bottom piece is rounded as shown at 14, so as to permit the front 90 piece 8 of the front section to engage under

95

the bottom piece, so as to hold the front section substantially in a horizontal position from the body section, when the front section is lowered as shown in Fig. 3. The 5 adjacent faces of the upper end of the side pieces 4 and 9 respectively are provided with angular recesses 15 and 16. One face of each recess 15 has secured thereto by the screws or the like 17 a wear plate 18. The 10 rear ends of the wear plates 18 terminate in rearwardly and upwardly extending ears 19 having eyes 20. The top section 21 of the box or case has its end edges provided with wear plates 22, secured to the top section 15 by means of screws or the like 23. The rear ends of the wear plates 22 have extensions 24 provided with openings 25. The openings 20 and 25 may receive any suitable pivoting means, such as indicated at 20 26, whereby the top section is pivotally connected to the body section. To one wall of each of the recesses 16 wear plates 27 are secured. When the front section is closed and the top section lowered, the top section 25 fits into the recesses 16, whereby the wear plates 22 may engage the wear plates 27, the bottoms of the recesses 15 and 16 acting to support the top section, which is provided with a suitable finger engaging ring 30 28 whereby the top section may be opened. Pivoted in any suitable manner at 29 to the end pieces 4 are hooks 30, to engage the headed pins 31 of the end pieces 9, to hold the front section closed. Secured at 32 to 35 one of the end pieces 4 and projecting above its upper edge is a plate 33, the projecting end of which has a slot 34. A carrying strap 35 is provided, and one end of the strap carries a snap hook 36 to engage the slotted 40 end of the plate 33. The other end of the strap 35 has a slot 37, to receive a stud 38 of a plate 39, which is secured in any suitable manner to the other end piece 4. The stud 38 carries a conventional form of turn 45 button 40, which after passing through the slot 37, may be turned transversely of the slot to prevent detachment of the carrying strap. The honey frames 41 may be arranged in the body section as shown in Figs. 50 2 and 3, in tiers, whereby the front section may be closed as shown in Fig. 2. The latches 30, are each in the form of a disk, which is pivoted at 29. Each disk latch has a cutaway portion 30^a forming a notch 30^b, 55 to engage the headed pin 31, the hook or overhanging part 30^c acting to prevent the closure section from opening. Each disk latch has a handle 30^d, in order to be grasped, so as to rock the disk latch to 60 cause the notch to engage and dis-engage the headed pin. The openings 30^e are provided in the disk latches, in order to lighten them. The improved portable case may carry suitable frames 30^g instead of the

honey frames. These frames 30^g shown in dotted lines in Fig. 3 have compartments 30^h for eggs.

The invention having been set forth what is claimed as new and useful is:—

1. In a transporting honey frame case, 70 a body section and a front section, the body section comprising opposing end pieces, rear and bottom pieces, and a pivotally mounted top piece, the bottom piece projecting forwardly of the end pieces, the lower portions 75 of the outer faces of the end pieces carrying forwardly extending metal straps being in parallelism with the end edges of the bottom pieces, the front section comprising a front piece and end pieces, the lower ends of 80 which being pivotally mounted between the metal straps and the end edges of the bottom piece, whereby the front section may be lowered so that its front piece may engage under the bottom piece to support the 85 front section in a horizontal line with the bottom piece, and means for locking the body and front section and top piece together.

2. In a transporting honey-frame case, 90 a body section and a front section, the body section comprising end, back and bottom pieces, and a top piece pivoted on the upper ends of the end pieces, the bottom piece extending forwardly of the edges of the 95 end pieces, said front section comprising end and front pieces, and means pivotally uniting the two sections, whereby the front piece may engage under the extension of the bottom piece for supporting the front 100 section in horizontal alinement with the bottom piece when opened, means for latching the two sections together, the upper ends of the inner adjacent faces of the end pieces respectively of both sections having recesses for the support of the top piece, and a carrying strap detachably connected to the end pieces of the body section. 105

3. In a transporting honey frame case, 110 the combination with a body section, of a front section having end pieces, said body section having a bottom having its front edge portion extended beyond the front edges of the ends of the body section, said front section having the lower ends of its 115 end pieces pivoted to the ends of the extended part of said bottom, the front edge of the extension of the bottom being curved in cross section concentric with the pivots of the front section, whereby the lower part of the front section may swing under and engage the lower face of the extension of the bottom and support the front section in a horizontal line with the bottom, means carried by the lower parts of the ends of the body section and being extended in parallelism with the ends of the extension of the bottom and receiving the ends of the pivots, 120 125

thereby reinforcing the pivots and the front section, and a top piece pivotally mounted to the upper parts of the ends of the body section and being countersunk between the upper parts of the ends of the body and front sections, and latching means for the two sections.

In testimony whereof I have signed my name to this specification in the presence of two subscribing witnesses.

HENRY D. GRAVES.
